UNITED STATES PATENT OFFICE

CHARLES E. BONINE, OF MELROSE PARK, PENNSYLVANIA, ASSIGNOR TO JAMES H. BELL, OF PHILADELPHIA, PENNSYLVANIA

REFRIGERATOR

Application filed October 24, 1929. Serial No. 402,206.

This invention relates to refrigerators, more particularly to refrigerators designed for use of solid carbon dioxide or the like.

Solid carbon dioxide, as is well known, is an exceedingly powerful refrigerant, while the gas itself rates very high as a thermo-insulating medium, its heat conductivity being determinable as averaging .0326 as against .0522 for air from determinations of several noted authorities, including Kundt, Winkelmann, Graetz, Schleiermacher, Müller, Eckerlein, Compan and Schwarze, on the subject.

The chief aim of my present invention is to utilize the indicated characteristic of the carbon dioxide gas in connection with solid carbon dioxide refrigerators through provisions whereby the sublimated gas, after prescribed circulation and recirculation around and through the chamber set apart for accommodation of the articles undergoing refrigeration, is caused to pass through previous material constituting the walls of the refrigerator before being permitted to escape into the atmosphere; all with a view toward securing the highest efficiency in the operation of the refrigerator, and the most economic use of the refrigerant.

Other objects and attendant advantages will be manifest from the detailed description following considered in connection with the attached drawings, wherein Fig. I is a plan view of a solid carbon dioxide refrigerator conveniently embodying my invention.

Fig. II is a longitudinal sectional view of the structure taken as indicated by the arrows II—II in Fig. I; and,

Fig. III is a transverse section taken as indicated by the arrows III—III in Figs. I and II.

As herein delineated, my improved refrigerator comprises a casing 5 in the form of a rectangular box with relatively thick previous end walls 6, side walls 7, top 8, and bottom 9, which are preferably made from suitably compressed fibrous thermo-insulation like "Kapok," although ground cork may be used if desired. This casing 5 I sheath completely in a jacket 10 of sheet metal which is gas-tight in all its joints but provided

near the tops of the opposite side walls 7 with apertures 10a, for a purpose later on explained. Within the hollow of the casing 5, I place an insert 11 of sheet metal that affords a main or refrigerating chamber 12 and a relatively smaller chamber or compartment 13, the latter being offset from one end of said refrigerating chamber and adapted to accommodate a charge of solid carbon dioxide B in block form. From Fig. II it will be noted that the chamber 12 and compartment 13 are individually accessible through openings 14, 15 in the top of the structure protected respectively by suitable tight fitting covers 16, 17. Like the casing 5 the covers 16, 17 are of fibrous insulation or cork sheathed within metallic jacketing. As shown, the end walls 18, 19 and the bottom 20 of the insert 11 are made hollow with provision of continuously communicating passages 21, 22 and 23 for circulation of carbon dioxide gas, as hereinafter disclosed. Referring to Fig. II it will be observed that the compartment 13 is only about half as deep vertically as the refrigerating chamber 12 and, furthermore, that it communicates through a series of horizontally arranged apertures 24 adjacent its bottom, with the passage 21 in the wall 18. The compartment 13 is also in communication with the refrigerating chamber 12 by way of apertures 25 in the double thickness wall 18 of the insert 11 near the top. The side walls 26 of the unit 11, on the other hand, are of single thickness metal and provided near their bottom with horizontally aligned apertures 27, that lead to narrow vertical clearance spaces 28 between said side walls and the insulate walls 7 of the casing 5. Also for a purpose to be presently explained, the inner thickness of the double wall 19 of the insert 11 is provided near the top with a horizontal row of perforations 29 by which communication is established between the passage 23 and the refrigerating chamber 12.

In the operation of the refrigerator, the cold heavier-than-air carbon dioxide gas liberated from the block B passes from the compartment 12 through the apertures 24 into the passage 21 in the hollow wall 18 of

55 60 65 70 75 80 85 90 95 100

the insert 11, then downward in said passage and across the passage 22, then upward in the passage 23 and into the refrigerating chamber 12 through the apertures 29. The 5 gas thus entering the chamber 12, in diffusing, passes about the articles under refrigeration in said chamber and, as thermal exchange takes place, returns for re-cooling to the compartment 13 through the aligned 10 apertures 25 in the double end wall 18 of the insert 11. In this way, a continuous circulation of the gas is maintained by thermal convection exteriorly around and through the chamber 12 to keep the articles under- 15 going refrigeration at the desired low temperature for preservation. Concurrently with such circulation however, a certain proportion of the gas enters the vertical spacial intervals 28 along the sides 7 of the insert 11 20 at the bottom, by way of the apertures 27, and diffuses through the interstices or voids in the insulate walls 6, 7 and 9 of the refrigerator casing 5. Here again it will be apparent that downward convection of the 25 cold carbon dioxide gas takes place with attendant upward displacement of the air initially entrained in the pervious casing walls, which air finds its way out of the openings 10a in the sheathing 10 and is eventually 30 supplanted entirely by the gas after operation of the refrigerator for a short time. By passage of the carbon dioxide gas through the insulate walls 6, 7 and 9, of the casing 5 35 in the manner explained, and as a consequence of its poor thermal conductivity, obviously I obtain a very much greater insulating effect than with air entrained in the insulation forming said walls, as would ordinarily be the case, with a corresponding 40 gain in the efficiency of the refrigerator as a whole.

Having thus described my invention, I claim:

1. In a refrigerator adapted for use of 45 solid carbon dioxide, a casing with pervious walls of thermo-insulate material affording a refrigerating chamber and an offset compartment for accommodation of the solid carbon dioxide, means providing opposing 50 hollow walls and a similar bottom for the chamber whereby circulation of the gas sublimated from the solid carbon dioxide about and through the refrigerating chamber is effected, and provisions affording com- 55 munication from the bottom of the refrigerating chamber whereby a portion of such circulation is diverted to intervals between opposing solid walls of said chamber for pas- 60 sage through and about the thermo-insulate 65 material of the casing before being permitted to escape into the outside atmosphere.
2. In a refrigerator adapted for use of 70 solid carbon dioxide, a casing with pervious walls of thermo-insulate material affording a 75 refrigerating chamber with an offset com-

partment for accommodation of the solid carbon dioxide, said chamber embodying substantially closed-in opposing hollow walls with a connecting hollow bottom and other opposed solid walls, one of the hollow walls 70 separating the offset compartment from the refrigerating chamber, means providing communication from the offset compartment into the separating hollow wall, means affording communication from the opposing hollow 75 wall into the refrigerating chamber and similarly from said chamber through the separating hollow wall into the offset compartment at a different level from the first mentioned means, whereby a constant circulation 80 of the gas sublimated from the solid carbon dioxide takes place first downwardly through one hollow wall, then below, and upwardly through the opposing hollow wall wholly exterior of the refrigerating chamber before 85 diffusion therein and return to the offset compartment for re-cooling, and means for diverting a portion of the circulating gas through the solid walls from a low level of the refrigerating chamber into the pervious 90 casing walls aforesaid.

3. In a refrigerator adapted for use of solid carbon dioxide, a metal-sheathed casing with pervious walls of thermo-insulate material affording a refrigerating chamber with 95 an offset compartment for accommodation of the solid carbon dioxide, said chamber having opposed hollow walls with a connecting hollow bottom and opposed solid walls, one of the hollow walls partitioning the offset compartment from the refrigerating chamber, aligned apertures providing communication from a low level of the offset compartment 100 into the partitioning hollow wall, similar orifices affording communication from a high 105 level of the opposed hollow wall into the refrigerating chamber and also from said chamber through the partitioning hollow wall into the offset compartment whereby 110 constant circulation of the gas sublimated from the solid carbon dioxide takes place downwardly, then below, and upwardly exterior of the refrigerating chamber before diffusion therein and return to the offset compartment for re-cooling, and other aligned 115 orifices whereby a portion of the gas in the refrigerating chamber is diverted from a low level through the solid walls for passage upwardly through the thermo-insulate material to effect displacement of entrained air in 120 the voids of said material before escape to the atmosphere by way of similar openings proximate the top of the metal sheathing.

In testimony whereof I have hereunto signed my name at Philadelphia, Pennsylvania, this 19th day of October, 1929.

CHARLES E. BONINE.
